UNITED STATES PATENT OFFICE.

EDMUND F. BARD, OF NEW YORK, N. Y.

ELECTRIC SYNCHRONIZING ATTACHMENT FOR CLOCKS.

SPECIFICATION forming part of Letters Patent No. 369,386, dated September 6, 1887.

Application filed September 9, 1886. Serial No. 213,132. (No model.)

To all whom it may concern:

Be it known that I, EDMUND F. BARD, a citizen of the United States, residing at New York, in the county and State of New York, have invented new and useful Improvements 5 in Synchronizing Apparatus for Time-Pieces, of which the following is a specification.

This invention relates to a class of apparatus employed for synchronizing time-pieces at determinate intervals; and it consists, essentially, in the combination, with a synchronizing device, such as a pair of arms or levers that are actuated to adjust the hands at determinate intervals by a cam or other means, of a motor which is constructed to adjust the hands through the intermediate mechanism, and a device for controlling the motor, such device being constructed to set the motor in action, to arrest its motion, and to retain the 15 motor out of action. This motor can be one of the well-known class of spring-motors, and its controlling device is actuated by a current of electricity. The time-piece is also provided with a circuit-closer, which, through 20 suitable electric connections, controls the current to the motor-controlling devices of similar time-pieces, so that all of a series of clocks are synchronized at one and the same time. A secondary dial and an index hand (or hands) 25 on each time-piece indicates the exact time at which the same was last regulated, and such index-hand can be actuated to move either by the motor or independently of the same, all of which is more fully pointed out in the following specification and claims, and illustrated in the accompanying drawings, in which—

Figure 1 represents a sectional front elevation of a clock provided with the improved synchronizing apparatus. Fig. 2 is a vertical section of the same in the plane $x x$, Fig. 1. Fig. 3 is a similar section thereof, showing the operating parts in a different position. Fig. 4 is a front elevation, with part broken away, of a clock provided with a modified form of mechanism for actuating the index-hands. Fig. 5 is a transverse vertical section in the plane $y y$, Fig. 4, of the index-hand-actuating mechanism.

Similar letters indicate corresponding parts. In the drawings, the letter A designates the 50 dial of a clock of ordinary construction. B is

the frame supporting the synchronizing apparatus, and C is a case inclosing the latter.

D D are levers which are fulcrumed at d to the case C, and from the lower extremities of 55 said levers project pins $d' d'$, that extend through a slot, a , formed in the clock-dial, and are adapted individually to engage with the minute-hand H of the clock at stated intervals, provided the same is within their arc of 60 vibration, and to bring it to a zero-point. When the levers D D are in their normal or open position, as shown by full lines in Fig. 1, the minute-hand H of the clock can freely pass by the pins on the said levers, as the same 65 now lie out of the arc of rotation of said hand.

The upper ends of the levers D D carry pins $d'' d''$, which project inwardly to be individually engaged by two series of cams, E E, that are mounted upon a spindle, E', and rotate with 70 the same, the said cams in their rotary motion causing the levers to close upon the minute-hand. The levers are reopened or spread apart by the action of springs F F, attached thereto.

The cam-bearing spindle E' is rotated at the proper intervals by its connection with a motor of any suitable construction—such as a spring or weight motor. In the example shown in the drawings a spring-motor is employed, S being its spring, and S' its center wheel, which latter is mounted upon an arbor, s, provided with a post for winding the spring, all being of the usual construction. The center wheel, S', is connected by pinions s' and s'' 85 with a pinion, e, on the spindle E', so that when the motor is in action the cams E E are rotated by said motor.

The mechanism for arresting the motion of the motor, for holding the motor out of action, and for allowing it to resume its action at the proper intervals is as follows: Upon the spindle E' is mounted an escapement-wheel, G, that is provided with two or more teeth, 1, 2, 3, and 4, Figs. 2 and 3, and such teeth are 95 adapted to be engaged by the arms $i i'$ of a detent-lever, I, that is fulcrumed at i^2 to a bracket or to the frame, and is subjected to the action of a spring, i^* . One end of said lever I carries an armature, I', Figs. 2 and 3, which 100 is in position to be attracted by electro-magnets J, so that when the armature is attracted

the escapement-wheel is released and the spring-motor is free to operate. An electric current may be passed through the bobbins to vitalize the cores through wires 10 and 11, 5 from any suitable station or from a primary clock, at the proper intervals and in the usual manner.

To utilize the power of the spring S of the motor as completely as possible, and to insure 10 perfect accuracy and a reliability in synchronizing, each series of cams contains four cams, E, and the escapement-wheel G and its detent-lever are peculiarly constructed. In the operation of the cams E, when the armature I' is 15 in its normal position, Fig. 2, the arm i of the detent-lever I engages the face of, say, tooth 1 of the escapement-wheel, and the levers D D are open, the pins d² d³ then resting at the outer edges of one of their respective cams E. 20 When the armature is attracted by the magnets, Fig. 3, the escapement-wheel is released and the spring S rotates the cam-bearing shaft E' through one-eighth of a revolution, at which point the tooth 3 of the escapement-wheel 25 comes into engagement with the arm i' of the detent-lever I, whereby the action of the motor is arrested. The cams E are so arranged 30 in relation to the pins on the levers D D that in the said one-eighth of a revolution they advance so as to bring the said pins quite to their inner ends, thereby closing the said levers to adjust the hand. When the circuit is broken and the armature is released, the detent-lever falls and tooth 3 of the escapement- 35 wheel is released. The motor again sets in action and continues until tooth 4 of the escapement-wheel is engaged by the arm i of the detent-lever, when the motion of the motor is again arrested. During this period the cams 40 are again moved one-eighth of a revolution to complete the quadrant, the pins on the levers D D go out of engagement with the cams, and said levers fly apart, Fig. 1.

If the minute-hand has not deviated from 45 the correct time to too great an extent in the course of its last revolution, one of the pins d² d³, according as the position of the hand is fast or slow, will move the same to the zero-point, which is shown to be at twelve o'clock. 50 The synchronizing mechanism of each signal or primary clock is so constructed that the instant it is set in motion it automatically opens and closes an independent electric circuit, by means of which any number of clocks 55 in the said circuit are synchronized at the same instant as the primary clock. In this way the several clocks located in stores or residences in towns or cities can be regulated at one and the same instant. The synchronizing 60 principle in each of these clocks is precisely similar to that heretofore described.

To close and break the circuit by the action 65 of the motor, a pinion, m, is mounted on the cam-bearing spindle E', which engages with a pinion, m', Figs. 2 and 3, upon a spindle, m², having bearings in the frame B. On this spindle is mounted an eccentric, M, the rod

m³ of which carries a contact, n, that is adapted to enter between two spring-plates, n' n', which are separated from each other by vulcanized 70 fiber or other insulating material. The end of the eccentric-rod m³ is composed of a non-conducting material and a strip of metal which overlies this material, so that when this contact n is thrust between the spring-plates the 75 circuit through a relay-battery, B², Fig. 2, is closed through wires 12 and 13, which are connected with the spring-plates. The shaft m² is so geared to the spindle E' that the eccentric makes four revolutions to one of the said 80 spindle—that is, one revolution for each of the cams E—and consequently the circuit from battery B² is closed and broken every time the clock is synchronized. Each clock can be provided with this transmitting mechanism 85 and a relay-battery, each and every clock then operating to close the circuit through the electro-magnets of the next following clock.

In order to facilitate the inspection of these 90 clocks, each clock has a secondary dial on its face, which are actuated either from the motor, as in Figs. 1 and 2, or by the works of the clock, as in Figs. 4 and 5, to indicate the exact time at which the clock was last synchronized.

As shown in Figs. 1 and 2, the secondary 95 dial A' is located on the dial of the clock in a position where it can be easily inspected, and the hand h is actuated by a gear-connection with the cam-bearing shaft E', the gear-wheels being so proportioned that with each revolution of the shaft E' through one quadrant the hand h is moved one-twelfth of a revolution or through a space corresponding to one hour of time—that is to say, every time the levers D D' close upon the hand H to synchronize the clock, the hand h of the secondary dial is moved to indicate the hour at which this synchronizing took place, and remains in its latter position until the expiration of another hour, when it is again moved. 100 The connection of the hand h with the motor may be varied as desired; and in the example I have shown a gear and shaft connection consisting of a bevel-gear on the cam-bearing shaft E', a bevel-gear on each end of a vertical 105 spindle, o, bevel-gears on the extremities of a horizontal spindle, o', and bevel-gears on the arbor o² of the hand h, which arbor is situated at right angles to the shaft o', all said gears properly engaging with their respective 110 drivers.

By comparing the time indicated by the 115 hands of the clock with that of the hand of the synchronizing attachment it can be readily perceived whether the synchronizing mechanism is in proper working order. The hand h of the secondary dial being actuated directly by the synchronizing apparatus, any failure of the latter to discharge its function is indicated 120 by this hand h, which in such a case remains in a position indicating the hour at which the clock was last synchronized, and therefore any existing difference in regard to the hours indicated by the respective hands will at once 125 130

suggest to the observer that the synchronizing apparatus is faulty.

As shown in Figs. 4 and 5, the index-hands h' h^2 are set in motion directly from the hour 5 and minute pinions of the clock, the mechanism being such that the hands are only moved at the time of synchronizing, and are then moved through a space corresponding to the 10 interval elapsing between the successive times of regulating.

The mechanism just referred to, which is fully described in principle in Letters Patent No. 300,833, dated June 24, 1884, is as follows, (see especially Fig. 5:) P is the arbor of the 15 minute-hand, and P' that of the hour-hand, and p⁰ p' p² are the respective pinions for obtaining the proper relative speeds of the hands, all as usual. R is a spindle located below the minute-arbor P, on which are loosely mounted the arbors r and r' of the minute and hour hands, respectively; and on each of said arbors is a pinion, R' R². Mounted on a stud, T, projecting from the frame is a pinion, t', and a second pinion, t², the two being secured to each other and 20 so arranged that the pinion t' meshes with the pinion R² and the pinion t² with pinion R', the diameter of the pinions being such that the hour-hand h' and minute-hand h^2 receive their proper relative speeds. Projecting 25 from the rear of the pinion R' are pins t, the free ends of which ride in slots formed in a disk, U. The hub of this disk is threaded to engage with a screw-thread formed on the spindle R. A circumferential ring, u, in which 30 there is a notch, u', is formed on the inner face of the disk U, the depth of this notch being a little less than the pitch of the thread on the spindle R—that is to say, one complete turn of the spindle would advance the disk a distance slightly greater than the depth of the 35 notch. The periphery is covered with small notches, which are engaged by a knife-edge, u², Fig. 4, carried by an upright armature-lever, U', which is pivoted at u³ in front of an electro-magnet, U³. A spring, q, is arranged so 40 as to hold the knife-edge u² normally against the periphery of the notched disk, so that as the spindle R is rotated by a gear-wheel, R³, thereon, which engages the pinion p² of the 45 clock-movement, the disk U is prevented from rotating, but is advanced toward the clock-dial by the action of the screw-thread on said spindle. The rotation of the spindle winds up the spiral spring V, one end of which is 50 secured in the hub of the disk U and the other end is fixed to the spindle R. A stop, v, arranged to engage with the notch u, projects from an arm, V', which is secured to the shaft R, and this shaft is so timed that when the 55 notch u is in engagement with it the hands h' h^2 will point to the correct time. If at each successive hour the knife is withdrawn from the periphery of the disk U, as when the armature-lever is attracted, the spiral spring causes 60 the disk to revolve, and the screw-thread on the shaft brings the disk toward the stop v, so that after making one revolution the notch u'

is brought into engagement with the stop v, and as, in revolving, the disk carries with it the arbor r and the pinion R', the minute-hand is advanced one hour, and the hour-hand, through its gear-connection therewith, is correspondingly advanced. The wires 14 and 15 of the electro-magnet are in one and the same circuit with the synchronizing attachment, and the disk U is released at the time of synchronizing, and the hands therefore indicate the exact hour and minute at which the clock was last synchronized.

When a series of clocks are synchronized 8c from a primary clock, the hands of the latter for indicating the time of synchronizing are in one and the same circuit with the synchronizing mechanism of all the clocks, so that a simple inspection of the hands of the primary 85 clock will show if the synchronizing mechanisms of all the clocks are in perfect working order, and the inspection of each and every clock is not necessary.

What I claim as new, and desire to secure 90 by Letters Patent, is—

1. A synchronizing apparatus for time-pieces, consisting of levers D D, engaging the minute-hand of the time-piece, a motor having a rotary spindle, E', the cams E on said spindle engaging the levers, the escapement-wheel G, the spring-pressed detent-lever engaging the said wheel, an electro-magnet, and electrical connections for the same, substantially as described.

2. A synchronizing apparatus for time-pieces, consisting of a mechanism engaging a hand of the time-piece, a motor for actuating this mechanism and containing a toothed wheel, G, and the oscillating detent-lever I, having two arms, i i', engaging alternately with the teeth of the said wheel, the wheel rotating through the space between two consecutive teeth for each complete oscillation of the lever, but having an intermittent motion, substantially as shown and described.

3. The combination of the levers D D, a motor, the spindle E' thereof, and the cams E, engaging the said levers, the escapement-wheels on spindle E', provided with teeth corresponding in number to the cams, a detent-lever having two arms engaging alternately with the teeth of the escapement-wheel, and means, substantially as described, for actuating the detent-lever, substantially as shown 115 and described.

4. In a synchronizing apparatus for time-pieces, the combination, with a mechanism for engaging and adjusting the hand at determinated intervals, of an index-hand for indicating the time of such adjustment, substantially as shown and described.

5. A synchronizing apparatus for time-pieces, consisting of a mechanism engaging the hand of the time-piece, a motor for actuating this mechanism, a stop for the motor, means, substantially as described, for actuating the said stop at determinated intervals, and an index-hand actuated by the motor to

indicate the time of synchronizing, substantially as shown and described.

6. A synchronizing apparatus for time-pieces, consisting of levers D D, engaging the 5 minute-hand of the time-piece, a motor having a rotary spindle, E', the cams E on said spindle and engaging the levers, the index-hand geared to the said spindle for indicating the time of synchronizing, a stop for the motor, 10 and means, substantially as set forth, for actuating the stop at determinated intervals, substantially as shown and described.

7. The combination, with the hand-adjusting mechanism, of a motor, a stop for the mo-

tor, means for actuating this stop, an eccentric 15 actuated by the motor, a circuit-closer, n, caused to reciprocate by the eccentric, contacts n' n' for the circuit-closer, and electrical connection of the contacts with a battery, substantially as shown and described. 20

In testimony whereof I have hereunto set my hand and seal in the presence of two subscribing witnesses.
